(57) **CLAIM**

The ornamental design for a cover for a binder, folder or notebook, as shown and described.

DESCRIPTION

FIG. 1 is a front perspective view of a cover for a binder, folder or notebook showing our new design;

FIG. 2 is a front view thereof;

FIG. 3 is a bottom end view thereof, the top end view being a mirror image thereof;

FIG. 4 is a rear view thereof;

FIG. 5 is a left end view thereof;

FIG. 6 is a right end view thereof;

FIG. 7 is a second embodiment of our design of FIG. 1;

FIG. 8 is a third embodiment of our design of FIG. 1; and,

FIG. 9 is a fourth embodiment of our design of FIG. 1.

The broken lines are for illustrative purposes only and do not constitute any part of the claimed design.

1 Claim, 7 Drawing Sheets
